LOOM THREAD CUTTER

Harrison N. Thibault, Hopedale, Mass., assignor to Draper Corporation, Hopedale, Mass., a corporation of Maine

Application October 26, 1956, Serial No. 618,638
8 Claims. (Cl. 139—268)

This invention pertains to improvements in thread cutters for looms, for example, temple thread cutters, of the type which function intermittently.

It is a general object of the invention to cut the period of time during which a temple thread cutter shall operate to a small fraction of the total weaving time of the loom.

A more specific object is that of devising a thread cutter of the type described which shall be pneumatically controlled to permit it to be actuated only at such times as there are threads closely within its range to be cut.

Other objects of the invention will become apparent from the following more detailed disclosure.

In automatic looms a thread cutter carried by a temple is provided to cut the outgoing and the ingoing ends at the selvage. Of course, the cutting function is required once after each replenishing cycle, but while that might involve operating the cutter for a few seconds, in practice, most looms function by actuating the cutter once for each beat of the lay. This means that the mechanism operates hundreds of times for the few picks during which it is needed with the attendant wear, noise and, of course, expense for repairs and replacements.

Attempts have been made to device cutters which shall function at desired times only and also some have been tried which function one pick out of every ten, for example. However, none of these has been practical enough to have gone into anything like commercial usage.

According to this invention, a more or less conventional cutter is provided with a means to latch it in an inactive position. At or about at the transfer cycle, and especially for a few picks thereafter, the cutter is unlatched by a mechanism pneumatically actuated. This pneumatic control is timed, preferably by being tied in with the transfer mechanism and the supply of compressed air for it may come from any convenient source.

The invention will be disclosed in detail by a description of one specific embodiment thereof as illustrated in the accompanying figures of drawing, wherein:

Fig. 1 is a plan view of a temple thread cutter with the invention applied thereto.

Fig. 2 is an elevation of the mechanism of Fig. 1.

Fig. 3 is an enlarged section taken at line 3—3, Fig. 1.

Fig. 4 is a front elevation of part of a loom showing the means by which the cutter is controlled.

Fig. 5 is a sectional view of a timer.

Fig. 6 is a plan view showing in detail the control for varying the time period.

Now referring to Figs. 1, 2 and 3, the cutter is mounted upon a temple having the usual bar 10, slide 11, head 12 and a roll enclosing pad and cap 13, the bar and cloth engaging parts of which reciprocate slightly when contacted by the lay at beat-up.

The cutter comprises a movable cutter blade 14 which shears the thread against a fixed blade 15. Blade 14 is a part of a slide or body part 16 from which depends a heel 17 by which the cutter is moved to the front and downwardly as an abutment at the lay strikes this heel. Normally, a spring 18 coiled about a pin 19 and attached by a loop at its other end to a pin 20 fixed in or integral with the heel 17 returns the cutter to the full line position, Fig. 2, after each cutting movement. The temple and cutter thus far described are not new and for a full disclosure of the construction and operation thereof,

2

reference is made to United States Patents 1,366,034 and 2,629,408.

While the cutter as above described would be operated once each pick of the loom, it is desired to confine its action to a relatively few cutting strokes at that time right after transfer when the ingoing and outgoing threads are to be cut at the selvage. Accordingly, a means is provided which disables it at all other times, this means being pneumatically controlled in its entirety.

10 A latch arm 21 is connected to the side of the head 12 at pivot 22 and is formed with a catch or latch 23 which is positioned to engage behind pin 20 and to latch the cutter in an inactive position. A spring 24 is coiled about pivot 22 and presses the arm down into latching engagement.

15 A cylinder 25 is threaded or otherwise secured in its head 26, Fig. 3, and these parts are fixed to the side of the temple slide 11 or to some other convenient stationary part by screws 27 and 28. A piston 29 and piston rod 30 are slidable in the cylinder and head respectively and are sealed against leakage of air pressure by O-rings 31 in the head and 32 on the piston. A spring 33 tends to keep the piston and rod in the position of Figs. 2 and 3.

20 Air under pressure is admitted to the cylinder through a line 34 connected at 35 to the head 26. Air first enters a chamber 36 in the head and then drives the piston against the spring 33. A port 37 permits the air at the atmospheric side to be expelled or to enter as the piston is actuated.

25 The rod 30 has an end 38 to which is connected one end of a link 39 the other end of which is attached at 40 to the end of latch arm 21. This latter connection is by a slot 41 in the link 39 so that the arm 21 may swing upwardly to permit the latching function. The link 35 is slightly offset to take care of the fact that the rod 30 and the latch arm 21 are not in vertical alignment.

30 It is quite possible to supply air under pressure to the loom from any common source or to compress it at the loom. This air may be for the purpose of controlling 40 the cutter only or, more preferably, may be supplied for other purposes so that the cutter control is only another useful function served.

35 By way of example, air may be conducted from a source to a combined timer-valve, Figs. 4, 5 and 6, entering at 42 and may have its pressure modified by a 45 reducing valve 43, if desired. This valve and timer are set and the cycle started by connection to some part of the transfer setting means. This timer-valve, generally indicated by numeral 44 is held in place by a bracket 45 attached to some fixed loom part such as the frame extension 46.

40 The combined timer and valve, Fig. 5 in particular, has a body which is divided into two cylindrically shaped parts 47 and 48. Air under desired pressure enters at 42 to a chamber 49 which is connected by a port 50 to a second chamber 51 in cylinder 47.

45 The chamber 49 is closed off from the outlet tube 52, the function of which is not of concern so far as the instant invention is concerned, by a valve 53. This valve seats on a washer 54 and is movable up or down on a stem 55. When lifted, air may flow past it to the space 56 and thence through tube 52. Normally air pressure maintains it closed.

50 Air in chamber 51 may pass to a tube 57 which connects at a T 58 to a tube 59 leading to a hollow transfer stud for purposes with which we are not concerned here. This tube 57 attaches to the timer body at a point opposite the space 60 formed about a perforated sleeve 61, a part of a plug 62. These hold a ring 63 and rubber or plastic washer 64 up in sealed contact with a shoulder at the lower end of chamber 51. These have a relatively large opening so as to provide for a space

about a timer stem 65 which passes up through the plug and has a flange 66 pinned or otherwise fixed in air tight relationship to it. At its top end this stem passes through a head 67 which seats against a shoulder in the chamber at which the size of the bore decreases to extend upwardly in a third part 68. A spring 69 between the head 67 and flange 66 tends to keep the stem in a position to maintain the flange seated on the washer 64 so that the air in chamber 51 may not enter the lower space 60.

Head 67 is sealed by O-rings 70 and 71. Above the head and at that extreme end of the stem a piston includes a cup or pump washer 72 and is held in place by a screw and washer and this, of course, will hold air pressure as the spring draws the assembly downwardly, but permits air to pass when moved in the opposite direction.

Chamber 68 is vented below the piston through an aperture 73. A head 74 is screwed to the top of this cylinder with a gasket between and is provided with means by which air may be permitted to bleed in slowly; here that means takes the form of a porous body of sintered metal 75 set in an opening 76 and held in place in any convenient manner. Here a bar 77, shown in plan in Fig. 6, may be swung to cover the porous plug 75 to a greater or lesser extent. This bar is held in any adjusted position by a screw 78.

In operating this timer-valve unit, the actuating impulse is taken from the transfer mechanism, more specifically, the starter shaft and an arm 79 movable therewith, Fig. 4. The arm 79 has connected to it a link 80 which extends upwardly to attach at 81 to an arm 82 fast on one end of a shaft 83. This shaft is carried in suitable bearings and has a finger 84 fixed at its opposite end and aligned below the timer stem 65 and valve stem 55. The finger is shown in dot-and-dash lines in a position it may take when the timer-valve is actuated. The link is adjustable for length and thus the swing of the finger may be so controlled as to displace the timer to a greater or lesser extent. It also opens the valve to admit air to the cylinder 42 and incidentally opens valve 53 also.

In operation, assuming that the cutter is latched in inactive position in which the lay in beating forwardly merely displaces the heel 17 slightly and the finger 84 is out of engagement with the timer and valve stems, when a replenishing cycle is started the arm 79 pushes link 80 upwardly to raise the finger 84. This pushes timer stem 65 upwardly to open valve 66 and admit air to the line 57 and thence through tube 34 to the cylinder to drive piston 29 and rod 30 to the left, Figs. 1, 2 and 3. This pulls the link 39 to the dot-and-dash position and raises latch arm 21 to release pin 20 and the movable cutter. The cutter then functions once at each beat of the lay in the usual manner.

Of course, the filling to be cut at the selvage will after a few picks, once the transfer is effected, come into range of the cutter and be severed.

The timer is set so that it will maintain the valve 66 open a short time after the ingoing and outgoing threads are cut, but the porous plug admits air slowly and in due time the piston descends and the valve is closed. As it closes the pressure drops in cylinder 25 and spring 33 then returns all parts to a position such that the latch arm 21 drops. At the next forward beat of the lay the pin 20 moves under the latch 23 whereupon the cycle is completed. The slot 41 permits the arm 21 to be raised against tension of spring 24 at that time.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

I claim:

1. In combination in a loom of the type having a reciprocating lay, a lay actuated thread cutter, means for latching said thread cutter in an inactive position, and pneumatic means for releasing the cutter for operation by the lay.

2. In combination in a loom of the type having a reciprocating lay, a thread cutter having a means engageable by a part of the lay in its operation thereby, a means for latching said cutter in an inactive position, and a pneumatically operated means for disengaging said latching means at such times as the cutter is to become operative.

3. In combination in a loom of the type having a reciprocating lay, a temple, a thread cutter carried by and movable with said temple and having a means engageable by a part of the lay in its operation thereby, a means for latching said cutter in an inactive position, and a pneumatically operated means for disengaging said latching means at such times as the cutter is to become operative.

4. In combination in a loom of the type having a reciprocating lay, a temple, a thread cutter carried by and movable with said temple and having a means engageable by a part of the lay in its operation thereby, a means for latching said cutter in an inactive position, and a pneumatically operated means comprising a cylinder, a piston in said cylinder and linkage operable by said piston when pressure is admitted to the cylinder for disengaging said latching means at such times as the cutter is to become operative.

5. In combination in a loom of the type having a reciprocating lay, a temple, a thread cutter carried by and movable with said temple and having a means engageable by a part of the lay in its operation thereby, a pin projecting from that means engageable by a part of the lay, a latching lever pivoted at said cutter and effective on said pin for holding the cutter in an inactive position, and a pneumatically operated means for disengaging said latching means at such times as the cutter is to become operative.

6. Mechanism as defined in claim 5 wherein said pneumatically operated means comprises a cylinder, a piston in said cylinder and linkage operable by said piston when pressure is admitted to the cylinder for disengaging said latching means at such times as the cutter is to become operative.

7. In combination in a loom of the type having a reciprocating lay, a temple, a thread cutter carried by and movable with said temple and having a means engageable by a part of the lay in its operation thereby, a means for latching said cutter in an inactive position, and a pneumatically operated means for disengaging said latching means at such times as the cutter is to become operative and timer means for controlling said pneumatically operated disengaging means.

8. In combination in a loom of the type having a reciprocating lay, a temple, a thread cutter carried by and movable with said temple and having a means engageable by a part of the lay in its operation thereby, a means for latching said cutter in an inactive position, and a pneumatically operated means for disengaging said latching means at such times as the cutter is to become operative and timer means responsive to displacement of air for controlling said pneumatically operated disengaging means.
